TRANSPOSITION ELIMINATOR FOR TYPOGRAPHICAL MACHINES

Application filed December 31, 1928. Serial No. 329,648.

This invention relates to linotype machines and more particularly to those parts thereof whose duty it is to assemble the matrices as the same are delivered under the control of 5 the keyboards of the machines.

A machine of the type to which reference is made includes an assembler entrance which comprises a number of vertical ways down which the matrices slide as they are selectively 10 released. The ways lead to the sloping surface of a downwardly moving matrix delivery belt, so that the rate of matrix movement to the assembler proper is controlled by the speed of the belt. The matrices lie flat on 15 the belt and therefore at an angle with the vertical, and in the assembling process these matrices must be arranged in parallel abutting relation, vertically positioned. Further, the matrices must be so assembled in the order 20 of depression of the corresponding keys of the keyboard. The matrices reach the belt ordinarily in their proper order, but they may be very closely spaced thereon, and particularly where this is the case, as the matrices 25 run off the belt there is a malfunctioning of the machine in that two matrices are assembled in transposed relation, the one which should follow, being ahead of the other.

It is an object of my invention, therefore, 30 to provide means for eliminating such transposition.

The exact nature of my invention together with further objects and advantages thereof will be apparent from the following description taken in connection with the accompanying drawings in which Fig. 1 is an assembly view more or less diagrammatic, showing pertinent parts of a linotype machine with my invention incorporated therein; Fig. 2 is an 35 end view of my transposition eliminator appearing in Fig. 1; and Fig. 3 is a detail section as in the horizontal plane of line 3—3, Fig. 1.

With reference now to the drawings, 1 is 40 a lower and driving pulley of the matrix delivery belt 2. 3 is the assembler star wheel. The pulley 1 and star wheel 3 have connection by gearing not shown whereby each rotates in counterclockwise direction Fig. 1, the star 45 wheel moving at high speed. 4 is an assem-

bler chute rail spring extending between the pulley and star wheel as indicated. 5 is the assembler slide carrying the upstanding assembler slide finger 6 and arranged for horizontal sliding movement as in the plane of 55 the paper. As will be appreciated by one familiar with the art the parts thus far described are old and well-known in the art, are carried by the face plate of the machine at the assembler entrance thereof, and are ordinarily concealed from view in the machine by the assembler cover which is indicated as removed.

Generally the operation of these parts is as follows: Matrices are delivered to the upper 60 stretch of the belt 2 under the control of the keyboard of the machine. The matrix A is thus shown lying flat upon the belt and moving downwardly therewith, to the left Fig. 1. As the belt is bent around the pulley 1 the 65 matrix is slid therefrom onto and down along the rail 4 until its lower end strikes one of the lobes of the star wheel 3, the matrix then being in the position as indicated at B. The star wheel as it revolves throws the matrix 70 from the rail 4 and flat against those which preceded it in the process and are assembled as at D against the finger 6, the slide 5 moving to the left Fig. 1 as matrices are added to the line.

The operations described will be recognized as included in the operation of a typical linotype machine; and it is when a matrix is in the position somewhat between the B and C positions indicated, that another matrix following the B matrix on the belt may in 75 sliding down the rail 4 jump over the B matrix and thus reach the line or stack D ahead of the matrix it was intended to follow.

According to my invention I provide 80 means for preventing such transposition, and comprising a flap member of flexible non-metallic and characteristically limp, yieldable but non-resilient, material, such as a trap of leather, duck webbing, or the like, of such 85 body as to have some stiffness and arrange to mount the member with its free end alongside the rail to be engaged by each matrix in 90 succession as the matrices move along the rail to enter the assembler. To this end I con- 95

veniently provide a bracket 7 securable with the space band chute 8 of the machine as by means of the screws 9 passing through suitable openings 10 in the vertical leg 11 of the bracket. The bracket 7 has a horizontal leg 12 adapted to stand out from the space band chute 8 as indicated, Fig. 1, when the bracket is so secured on the machine. This leg 12 of the bracket carries a bolt such as the thumb screw 13, between the head of which and the arm may be secured an end 14 of the strap 15. A member 16, preferably resilient but less limber than the strap, is provided as backing means therefor, having an end also secured under the head of the thumb screw and its opposite end extending downwardly as at 17. The free or lower extremity 18 of the strap member 15 extends below that of the backing member 16 and the free extremities of both these members lie generally alongside the rail 4. The portion of the backing member underlying the thumb screw 13 is slotted as at 19 to clear the bolt or screw portion 20 of the thumb screw whereby the position of the depending portion 17 of the backing member may be adjusted to vary its clearance from the chute 4. The corresponding secured end of the strap 15 may be similarly slotted or may simply have an opening 30 through which the member 20 passes. In either event, adjustment of the backing member effects corresponding adjustment of the free end 18 of the strap, and such adjustment is made dependent upon matrix thickness as will be understood by one familiar with the art. The adjustment is preferably such that the largest matrix of the font to be handled will have contact at least with the end 18 of the strap as it slides down the chute 4.

40 Thus when proper adjustment is made the free end of the strap forms a sort of flap member having frictional properties and engageable by each matrix in succession as the matrices move along the rail to enter the assembler.

45 When the parts are so mounted upon the machine and the proper adjustment is made it will be found that the extremity of the flap member 18 lies in the path of space bands delivered through the chute 8. Thus a buffering effect is had upon the space bands, saving the usual wear and tear particularly upon the space band lugs.

50 I have found in practice that transposition is made practically impossible by the proper employment of my device as described. While I am not prepared to exactly analyze the reasons for such accomplishment it may well be that the matrices have a slight wedging effect between the free ends of the described eliminator parts and the chute, or at least occupy so much of the clearance therebetween as to make it impossible for a matrix succeeding on the belt to overrun a preceding matrix between these parts.

What I claim is:

55 1. In a linotype machine having a matrix assembler and a matrix rail leading thereto, means for eliminating transposition of matrices at the entrance to the assembler and comprising a non-metallic flap member of yieldable but non-resilient material and a metallic backing member for supporting said flap member with its free end overhanging the backing member and alongside the rail, 70 to be engaged by each matrix in succession as the matrices move along the rail to enter the assembler.

80 2. In a linotype machine having a matrix assembler and a matrix rail leading thereto, means for eliminating transposition of matrices at the entrance to the assembler and comprising a flap member of yieldable but non-resilient material and a backing member for supporting said flap member, and means associated with said members for securing one of the ends of each in independently adjusted relation, to position the opposite and free ends thereof alongside the rail, with that of the flap member overhanging that of the 85 backing member to be engaged by each matrix in succession as the matrices move along the rail to enter the assembler.

85 In testimony whereof I hereby affix my signature.
